United States Patent Office

Des. 220,698
Patented May 11, 1971

220,698

TELEPHONE TERMINAL

Henry Kapper, Raleigh, N.C., assignor to International Business Machines Corporation, Armonk, N.Y.

Filed Dec. 31, 1969, Ser. No. 20,928

Term of patent 14 years

Int. Cl. D14—03

U.S. Cl. D26—14

FIG. 1

FIG. 2

FIG. 3

FIG. 4

FIG. 1 is a front perspective of a telephone terminal, showing my new design;

FIG. 2 is a perspective view taken from the rear and right side.

FIG. 3 is a left side elevational view.

FIG. 4 is a top plan view.

I claim:

The ornamental design for a telephone terminal, as shown.
